DESIGN FOR AN AUTOMOBILE

Charles Stanley Prince, Washington, D. C.

Application April 3, 1933, Serial No. 47,682

Term of patent 7 years

To all whom it may concern:

Be it known that I, CHARLES STANLEY PRINCE, a citizen of the United States, residing at Washington, in the District of Columbia, have invented a new, original, and ornamental Design for Automobiles, of which the following is a specification, reference being had to the accompanying drawings, forming part thereof.

Fig. 1 is a side elevation of my new design.

Fig. 2 is a front perspective view thereof; and

Fig. 3 is a plan view thereof.

Fig. 4 is a side elevation of the front portion of the design, the bumper being omitted.

Fig. 5 is a plan view of the part shown in Fig. 4; and

Fig. 6 is a front elevation of my design, the bumper being omitted.

One of the predominant and characteristic features of the design is the fact that the front thereof comprises a radiator screen, the major part of which is curved convexly about a transverse horizontal axis, and flanked on either side by a similarly curved solid portion which merges with the surface of the hood.

I claim:

The ornamental design for an automobile, as shown and described.

CHARLES STANLEY PRINCE.
